PEDESTAL FOR A BALANCE BLOCK GAME

Clifford Duane Hitterdal, P.O. Box 3,
Hitterdal, Minn. 56552

Filed Jan. 14, 1974, Ser. No. 433,225

Term of patent 14 years

Int. Cl. D21—01
U.S. Cl. D34—15 N

Fig. 1

Fig. 2

Fig. 3

Fig. 4

FIG. 1 is a right-front perspective view of a pedestal for a balance block game showing my new design;
FIG. 2 is a top plan view thereof;
FIG. 3 is a side elevational view thereof; and
FIG. 4 is a rear elevational view thereof.

I claim:

The ornamental design for a pedestal for a balance block game, substantially as shown and described.
